US0D1100453S

(12) United States Design Patent (10) Patent No.: US D1,100,453 S
(45) Date of Patent:  Nov. 4, 2025

(54) SHOE

(71) Applicant: NIKE, Inc., Beaverton, OR (US)

(72) Inventor: Hector Gonzalez, Beaverton, OR (US)

(73) Assignee: NIKE, Inc., Beaverton, OR (US)

() Term: 15 Years

(21) Appl. No.: 29/932,740

(22) Filed: Mar. 15, 2024

(51) LOC (15) Cl. 02-04

(52) U.S. Cl.

USPC D2/947; D2/953
